UNITED STATES PATENT OFFICE.

MAHLON HORACE SNYDER AND FULTON H. SMITH, OF PHILADELPHIA, PENNSYLVANIA.

MECHANICAL TOY.

Application filed September 11, 1922. Serial No. 587,299.

To all whom it may concern:

Be it known that we, MAHLON HORACE SNYDER and FULTON H. SMITH, citizens of the United States, residing at Philadelphia, in the county of Philadelphia and State of Pennsylvania, have invented new and useful Improvements in a Mechanical Toy, of which the following is a specification.

Our invention relates to a new and amusing mechanical toy, and has for its object to provide a device of this character that will be actuated by weights in the form of balls.

Another object of the invention is to provide a mechanical toy wherein different devices are successively actuated by weights, said weights being successively discharged from a hopper located at the highest elevation of the toy.

A further object of the invention is to provide a framework having tracks with cars running thereon and actuated by weights discharged from one car to another, said weights being sufficient to carry the cars down their respective tracks and when discharged therefrom permit the cars to be returned to their normal positions through the medium of suspended or captive weights.

A still further object of our invention is to provide means for unlatching the doors of the different cars when properly positioned for the discharge of a ball weight therefrom.

Other objects of our invention are to provide means for positively closing the door of one of the cars and to provide means to prevent the accidental dislodgement or derailment of one of said cars.

With these ends in view, this invention consists in the details of construction and combination of elements hereinafter set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1, is a side elevation of the mechanical toy embodied in our invention.

Fig. 2, is an end view thereof.

Fig. 3, is an enlarged fragmentary plan view of the toy. 55

Fig. 4, is a further enlarged bottom plan view of one of the cars.

Fig. 5, is a side elevation thereof.

Fig. 6, is an enlarged end view of the 60 suspension car.

Fig. 7, is an enlarged fragmentary plan view of the elevator.

Fig. 8, is a side elevation thereof.

Fig. 9, is an enlarged fragmentary sectional side elevation of the upper portion of the framework. 65

Fig. 10, is a section at the line 10—10 of Fig. 9.

Fig. 11, is a view similar to Fig. 9 of the 70 lower portion of the framework.

Fig. 12, is a fragmentary plan view of the connection between the upper end of one of the rails of the track and the framework. 75

Fig. 13, is a similar view at the lower end of one of the rails of the track.

Fig. 14, is an enlarged fragmentary sectional side elevation of the upper portion 80 of the toy in the region of the hopper.

Fig. 15, is an end view thereof.

Fig. 16, is a plan view of one of the suspended or captive weights.

Fig. 17, is a side elevation thereof.

In carrying out our invention as here embodied, 2 represents a skeleton like framework comprising a tall tower 3, a short tower 4, an inclined two rail track 5 adjacent the lower end of the framework and a monorail 6 at the upper end of the framework. 85 90

At the base of the tall tower 3 is a stand 7 having notches 8 to receive the ends of the rails 9 of the two rail track 5 the ends of said rails being also notched as at 11 so 95 as to hold the lower ends of the track rails in their proper positions in the stand, while the upper ends of these track rails are also notched as at 12 and set in notches 13 in the cross bar 14 carried by the short tower 100 at a point intermediate its height and with said rails are connected spacing members 15 one of which is slightly longer than the width of the track so as to provide wings 16 in which are detachably mounted the 105 downturned ends 17 of the torque rods 18

the opposite downturned ends 19 of said rods being detachably mounted in suitable sockets 20 carried by the legs or uprights of the short tower.

5 The upper ends of the rails 9 of the track 5 are turned up as indicated at 21 and to these upturned ends is secured a hanger 22 which acts as a tipping means for the elevator to be later described and also as a 10 bearing for the shaft or axle of the grooved pulley 23 over which runs a flexible cable 24, such as a piece of string, said cable running over another grooved pulley 25 supported by the bracket 26 projecting from 15 the upper end of the short tower. On one end of this cable is fastened a suspended or captive weight 27 while the other end of the cable is secured to a car 28 running upon the track 5 and normally held at the 20 upper end thereof by the weight 27. This car 28 includes a body 29 suitably mounted upon the flanged wheels 30, for running upon the rails of the track and provided with an eye 31 by which the cable is secured to the car. The body of this car is 25 open at the top and at one end, said open end being the lower end of the car when considered as mounted upon the inclined track 5, and said open end is normally 30 closed by a door 32 hinged as at 33 to brackets or their equivalent on the sides of the car body and this door is normally 35 closed by gravity which is maintained in its closed position by a spring actuated catch 34 mounted on the outside of the car body with the nose engaging one side edge of the door. This spring actuated catch is provided with a trigger 35 which when the car has reached its lowermost position on the 40 track will contact with a catch throwing arm 36 located in the path of travel of the catch trigger and supported by the stand 7 at the base of the tall tower.

At the upper end of the short tower is 45 located an elevator 37 arranged for vertical movement between the upper portion of said tower and the upper end of the track 5. As shown in Figs. 7 and 8, this elevator comprises a body 38 open at the top and at one 50 end the latter being normally closed by a door 39 hinged as at 40 to the upper portions of the sides of the body and this door is normally maintained in its closed position by gravity. This elevator has a bale 41 for 55 suspending said elevator from a flexible cable 42 running over grooved pulleys 43 and 44 suitably mounted on the upper portion of the short tower and to the opposite end of said cable is fixed a suspension or captive 60 weight 45 for normally maintaining the elevator in a raised position, as shown in Fig. 2. This elevator also carries oppositely disposed guide brackets 46, which if found desirable may be formed from the same material or wire producing the bale 41, the said

guide brackets coacting with the parallel portions of the legs of the short tower and loosely fitting said legs so that the elevator may be tilted when its closed end contacts with the hanger 22 during the downward 70 travel of the elevator.

The monorail track 6 carries posts 47 and 48 either formed therewith or secured thereto which fit in sockets 49 and 50 at the upper ends of the tall and short towers respectively, and the lower end of said monorail track has a hook 51 formed from its lower end which acts as a stop for the suspension car 52.

This suspension car comprises a body 53 80 open at its top and one end of said open end being normally closed by a door 54 pivoted as at 55 to the upper portions of the side walls of the body. Said door closed by gravity is normally maintained in a closed 85 position by the spring catch 56, similar to that shown in Figs. 4 and 5, said catch having a trigger 57 to be actuated by a trigger throwing member 58 secured to the upper end of the short tower in the path of travel 90 of the catch trigger on the suspension car. At one side of the car body 53 is connected one end of the hanger 59, the opposite end being connected with the truck or carriage 60 suitably mounted on a pair of grooved 95 wheels 61 adapted to run upon the monorail track 6.

To the truck carriage 60 is fastened one end of a flexible cable 62 running over a grooved pulley 63 at the top of the tall tower 100 and having a suspended or captive weight 64 attached to the opposite end, said weight normally holding the suspension car at the top or upper end of the monorail track. The weight 64 preferably has a set of coacting fingers 65 for engagement with the guides 66 secured to the tall tower which will maintain the weight 64 in its proper path of travel.

105 Adjacent the upper end of the tall tower is located an extension plate 67 having pockets 68 to receive the ends of the brackets 69 which support the inclined hopper 70 in such position that its lower open end overlies a body of the suspension car 52 when the latter is at the top of the monorail track, as plainly shown in Fig. 14, and this lower open end of the hopper is preferably curved as at 71 so that said open end will overlie the suspension car as above stated, although 115 the main portion of the hopper is set to one side of the monorail track.

120 Adjacent the lower open end of the hopper are located brackets 72 between which is pivoted the walking beam 73 carrying the depending pivoted fingers 74 and 75 sliding through guides 76 supported by the hopper and spaced apart a distance approximately equal the diameter of one of the balls 77 shown in Fig. 14. The walking beam 73 is 125 130

actuated by the weighted arm 78 when the truck or carriage of the suspension car rides thereunder.

At the bottom of the tall tower in line 5 with the two rail track 5 is a pan or ball catching device 80 which is adapted to rest upon the same surface on which the framework of the toy rests and this pan preferably has lips 79 to engage the base of said 10 tall tower for properly positioning it.

From the foregoing it will be seen that the torque rods may be detached, the different cars removed from the framework, then the tracks and the hopper detached from the 15 towers, thus providing for disassembling the toy so that it may be packed or stored in a small and compact space making it easy to handle for shipping purposes.

The operation of the toy is as follows:—
20 A number of balls 77 are placed in the hopper 70 and the suspension car 52 moved downward along the normal track to or toward its lower end and as soon as this car is released the captive or suspended weight 25 64 will cause said suspension car to travel upward along the monorail track. As soon as the truck or carriage of the suspension car rides under the weighted arm 78 so as to lift its outer end the walking beam 73 30 will be oscillated to disengage the finger 75 from the foremost ball 77 so as to permit said ball to roll down and out of the hopper. At the same time the finger 74 will have engaged the succeeding ball to retain all the 35 other balls in the hopper. As the foremost ball drops into the body of the suspension car its weight added to that of the suspension car will overbalance the weight 64 and cause the suspension car to travel down the 40 inclined monorail track.

As soon as the suspension car has traveled a sufficient distance to release the weighted arm 78 the walking beam will be returned to the position shown in Fig. 14 so that all 45 of the balls in the hopper will move downward until the then foremost one engages the finger 75.

When the suspension car has traveled to the lower end of the monorail track, as 50 shown by dotted lines in Fig. 1, the trigger 57 of the spring catch 56 will contact with the trigger throwing member 58 to release the door 54 which will permit the ball in the suspension car to roll therefrom into the elevator 87 permitting the weight 64 to return the suspension car to its normal position at the upper end of the monorail track.

As the ball weight 77 drops into the elevator this additional weight will cause the 55 elevator to travel downward against the action of its captive weight 45. As soon as the elevator reaches its lowermost position it will contact with the hanger 22, as shown by dotted lines in Fig. 1, causing said elevator 60 to tilt because of the loose fit of the guide

brackets 46 on the legs of the short tower and as the elevator is tilted the ball weight will roll toward the door 39 and force the same open allowing said ball weight to roll into the car 28 and as soon as this ball 70 weight has left the elevator the weight 45 will return said elevator to its normal raised position.

The additional weight added to the car 28 by the ball 77 dropping therein will cause 75 the car 28 to run down the track 5 and when reaching its lowermost position the trigger 35 will engage the trigger throwing member 36 so as to unlatch the door 32 and permit the ball weight to roll into the pan receptacle 80 from which point they may be returned to the hopper.

Should the opening of the door 32 on the car 28 lift said door to such a height that it should remain open as the car 28 has returned to its normal position at the top of the track 5 by the weight 27 said door will contact with the projection 88 to move it to a position where it will drop by gravity.

In order to prevent the car 28 from becoming derailed as it reaches either end of the track 5, we provide rods 81 and 82 at the top and bottom of the track respectively which are substantially parallel with said track and of such height that the car axles 95 will run beneath them.

Of course we do not wish to be limited to the exact details of construction as herein shown as these may be varied within the limits of the appended claims without departing from the spirit of our invention.

Having thus fully described our invention, what we claim as new and useful is:—

1. A mechanical toy comprising a tall tower, a short tower, an inclined monorail track connected with the upper ends of said towers, a two rail track connected with the lower portion of the tall tower and with the short tower at a point intermediate its height, cars mounted to run on said tracks, means to normally maintain the cars at the highest points of their respective tracks, an elevator mounted on the short tower to operate between the low point of the monorail track and the high point of the two rail track, means to normally maintain the elevator in a raised position, and means to successively release ball weights so as to enter the car on the monorail track and cause said car to convey the ball weight to the elevator, said elevator conveying the ball weight on the car of the two rail track which latter conveys said ball weight to the base of the tall tower.

2. A toy of the class described consisting of a tall tower, a stand at the base thereof, a short tower, a two rail track detachably connected with the tall tower at its base and with the short tower below its upper end, a monorail track detachably connected with

the upper ends of said towers, a suspension car mounted to run on the monorail track and adapted to be moved in one direction by a weight connected therewith, means detachably connected with the upper end of the tall tower for successively releasing ball weights one of which upon entering the suspension car will cause the same to move along the track in the opposite direction, an elevator mounted on the short tower and normally maintained in its elevated position by means of a weight connected therewith, means for releasing the ball weight from the suspension car so as to enter the elevator and cause it to move downward, a car

mounted to run upon the two rail track and normally held in a position adjacent the path of travel of the elevator by means of a weight connected therewith, means to release the ball weight from the elevator to permit it to enter the last named car, said ball weight causing said last named car to travel along its track in one direction, means to release the ball weight from said car, and a receptacle to receive said ball weight.

In testimony whereof, we have hereunto affixed our signatures.

M. HORACE SNYDER.
FULTON H. SMITH.
